UNITED STATES PATENT OFFICE.

ALFRED HUFFNAGLE, OF PHILADELPHIA, PENNSYLVANIA.

DESIGN FOR WATCH-CHARM AND MEMENTO.

Specification forming part of Design No. **7,164**, dated February 10, 1874; application filed January 26, 1874.
[Term of Patent 3½ years.]

To all whom it may concern:

Be it known that I, ALFRED HUFFNAGLE, of Philadelphia, in the county of Philadelphia and in the State of Pennsylvania, have invented a new and Original Design for a Memento Dedicated to the Memory of the Fifty-Six Signers of the "Declaration of Independence;" and do hereby declare that the following is a full, clear, and exact description thereof.

My design consists, principally, in the form of the memento or charm, which, as seen in the drawings, has a rectangular form in horizontal section, and from its base has upward and inward inclining sides. At its upper end said charm is surmounted by a ring, while upon one of its sides, at its vertical center, are placed the figures 56, above the same the words and figures "July 4th, 1776," and below said figures 56 the words and figures "July 4th, 1876," the

same being commemorative of the fifty-six signers of the Declaration of Independence, the date of such Declaration, and the date of the centennial anniversary of the same.

The remaining faces or sides of the charm may contain other suitable inscriptions, if desired.

Having thus fully set forth the nature and merits of my invention, what I claim as new is—

The design for a watch-guard charm or memento, substantially as described and shown.

In testimony that I claim the foregoing, I have hereunto set my hand this 19th day of January, 1874.

ALFRED HUFFNAGLE.
